(57) **CLAIM**

The ornamental design for a slide holder, as shown and described.

DESCRIPTION

FIG. 1 is a perspective view of the design of the present disclosure;

FIG. 2 is a top view thereof;

FIG. 3 is a front view thereof;

FIG. 4 is a rear view thereof;

FIG. 5 is a bottom view thereof;

FIG. 6 is a first side view thereof; and,

FIG. 7 is a second side view thereof.

The dash-dash broken lines seen in the drawings illustrate environmental structure and the dot-dash broken lines illustrate the bounds of the claim; all broken lines form no part of the claimed design.

1 Claim, 3 Drawing Sheets

FIG. 1

FIG. 2**FIG. 3****FIG. 4**

FIG. 5**FIG. 6****FIG. 7**
